UNITED STATES PATENT OFFICE.

CHARLES L. BURDICK, OF LONDON, ENGLAND.

STENCIL-CLEANING DEVICE.

978,984.

Specification of Letters Patent. Patented Dec. 20, 1910.

Application filed March 6, 1909. Serial No. 481,774.

To all whom it may concern:

Be it known that I, CHARLES L. BURDICK, a citizen of the United States, residing at London, in the county of Middlesex, England, have invented a certain new and useful Improvement in Stencil-Cleaning Devices, of which the following is a full, clear, concise, and exact description, reference being had to the accompanying drawings, 10 forming a part of this specification.

My invention relates to a cleaning or wiping apparatus, particularly to apparatus for wiping and cleaning stencils through which paint or coloring matter is applied to material to be decorated.

Heretofore stencils have been cleaned with rags or blotting material, or wiped with a simple form of flexible wiper, which has the effect, when much liquid is present, of wiping the surplus color into the openings in the stencil, thus causing discoloration and spoliation of the material to be decorated. In the device of my invention, provision is made for carrying away the paint or coloring matter immediately after it is wiped up and any accumulation of paint or coloring matter is prevented so that the stencil will be kept entirely clean and discoloration and spoliation of the material prevented.

30 My device comprises a wiping surface or surfaces adjacent which is an inlet for air, which inlet is valve-controlled and adapted for connection with a suction source so that immediately after the coloring material is 35 wiped from the stencil, it is carried with the air and prevented from accumulating.

My invention contemplates a construction in which the valve mechanism is automatically actuated by the use of the cleaning device itself; that is, the application of 40 the device to the stencil opens the valve to establish communication between the source of suction and the wiping means, and the removal of the cleaning device from the stencil 45 serves to close the valve to prevent such communication.

My device is shown in detail in the accompanying drawings, in which—

Figure 1 shows my invention in longitudinal sectional view. Fig. 2 is a plan view of a portion of the device shown in Fig. 1; and Fig. 3 shows in detail view a modified 50 form of openings for removing the color taken from the stencil by the wiping means. 55 The main part or body of the device is in the form of a cylindrical hollow casting 1,

which contracts at its front end into a neck 2, which at its end supports the wall 3, which is disposed at an angle, and which may be cast integral with part 1. The other end 4 of the part 1 has a reduced part for receiving a hose or other flexible conductor 5. The member 1 carries at its upper end a prismatic casing 24, in which a member 25 is adapted to slide. The member 25 is normally thrust outward in the casing 24 by means of a spring 26 and is prevented from moving in either direction beyond certain limits by a stop screw 27 secured in the member 25 and working in a slit 28 in the casing 24. The member 25 carries, in a pocket at its outer edge, wiping surfaces or strips 13 and 14 held in place by a rectangular frame 17. The member 25 is hollow and its interior is in communication 75 with the opening 18 in the frame 17. A port 29 is formed in the lower side of the member in such a manner that when the member 25 is moved into the casing 24 by pressing the wiping strips 13 and 14 upon 80 the stencil, this port is brought into alignment with the inlet 12 in the neck 2, and thus communication is established between the source of suction and the opening 18 formed adjacent to the wiping strips or surfaces. As a result of the construction just described, it is apparent that when the device is applied to the stencil the member 25, which is in effect a valve, is moved to a position to remove the coloring matter accumulated at the opening 18, and that the removal of the device from the stencil permits the spring 26 to move the valve member 25 outward to interrupt the communication between the source of suction and the opening 85 90 95 18.

As shown in Fig. 3 the opening 18 may be suitably divided, if desired, into a number of small openings 18^a, which for some classes of work may be found desirable. 10

The detail construction of my device can of course be changed and still come within the scope of my invention, and I therefore do not wish to be limited to the precise arrangement shown.

Having described my invention, I desire to secure the following claims by Letters Patent:

1. In a device for cleaning stencils, the combination with a handle part having a 11 passageway extending therethrough, of a casing carried by said handle and having

- one end thereof open, a hollow sliding valve member in said casing, said valve member having one end thereof open and having a port arranged for connection with said passageway, a wiping member carried adjacent the open end of said valve member, and means tending to hold said valve member so that the port therein will be out of alinement with said passageway.
2. In a device for cleaning stencils, the combination with a handle part having a passageway extending therethrough, of a casing having an open end carried by said handle, a hollow sliding valve member in said casing and extending outside said open end, said valve member having an open end and a port for connection in alinement with said passageway, a wiping member carried adjacent the open end of said valve member, spring means tending to hold said valve member so that the port therein will be out of alinement with said passageway, and means for limiting the movement of said valve member.
3. In a device for cleaning stencils, a supporting frame having a passageway, a valve piece carried by said frame for controlling the continuity of said passageway, said valve piece having an open passageway adapted for communication with said first-named passageway, resilient means tending to move said valve piece to close said first-named passageway, and wiping material carried by said valve piece at the open end of the passageway thereof, said valve piece being moved into position to establish communication between said passageways by pressure applied at said wiping material.
4. In a device for cleaning stencils, a portable supporting frame, a wiping piece carried by the frame, said frame having a passage-way opening adjacent to said piece, and a valve in said passage-way automatically operative to open said passage-way when

said wiping piece is applied to the stencil and for automatically closing said passageway when said wiping piece is removed from the stencil.

5. In a device for cleaning stencils, a supporting frame having a passageway, a valve piece carried by said frame for controlling the continuity of said passageway, said valve piece having a wiping surface and an open passageway thereat adapted for communication with said first-named passageway, and resilient means tending to move said valve piece to close said first-named passageway, said valve piece being movable against the tension of said spring into position to establish communication between said passageways by pressure applied at said wiping surface.

6. In a device for cleaning stencils, a supporting frame having a passageway, a valve piece carried by said frame for controlling the continuity of said passageway, said valve piece having an open passageway adapted for communication with said first-named passageway, resilient means tending to move said valve piece to close said first-named passageway, and wiping and collecting material carried by said valve piece adjacent the open end of the passageway therein, said wiping and collecting material being flexible and subject to pressure applied to said frame, and said valve piece being moved into position to establish communication between said passageways by pressure applied at said wiping and collecting material.

In witness whereof, I hereunto subscribe my name this 26th day of February A. D. 1909.

CHARLES L. BURDICK.
